SWING

Lucien Vermette, Yonkers, N. Y.

Application August 3, 1943, Serial No. 497,206

3 Claims. (Cl. 155—60)

My invention relates to amusement devices, and has among its objects and advantages the provision of an improved swing which may be oscillated by the occupant without the aid of any outside source.

In the accompanying drawing:

Figure 1 is a front elevational view of a swing in accordance with my invention; and

Figure 2 is a view taken along the line 2—2 of Figure 1.

In the embodiment selected for illustration, I make use of a base 10 upon which is mounted side frames 12 comprising beams 14 converging upwardly and fixedly secured one to the other by plates 16 bolted to the members. A shaft 18 is fixedly secured to the plates 16, and a gear 20 is fixedly secured to the shaft.

Depending from the shaft 18 is a swing unit 22 comprising a box-like enclosure 24 having a seat 26 mounted therein and a seat back 28 associated with the seat. A shaft 30 extends across the enclosure 24 vertically of the forward edge of the seat 26 and spaced equal distances from the back and front walls 32 and 34, respectively. To the shaft 30 is pivotally connected two bars 36 having their upper ends pivotally connected with the shaft 18. Straps 38 are secured to the enclosure 24 for supporting the shaft 30.

A bracket 40 is secured to each of the bars 36 for rotatably supporting a shaft 42 having a crank 44 formed therein. A gear 46 is fixed to the shaft 42 and is arranged in mesh with the gear 20.

To the crank 44 is pivotally connected two bars 48, each pivotally connected at its lower end with a shaft 50 adjacent the sides 52 of the enclosure 24 and closely adjacent the front wall 34. Plates 54 are secured to the enclosure 24 for supporting the shaft 50, the latter lying in parallelism with the shaft 30. Shaft 42 lies in parallelism with the shaft 18 and the gear 20 is coaxial with the shaft 18.

In operation, a person enters the box-like swing enclosure 24 of swing unit 22 and occupies the seat 26 and upon leaning back and forth sets the swing initially in motion by shift of weight which in turn is translated through bars 48 connected

to crank 44 into movement of gear 46 about fixed gear 20—crank 44 being offset with respect to bars 36—so that continued shifting of weight further increases the oscillation movement which may approach three hundred and sixty degrees.

Without further elaboration, the foregoing will so fully illustrate my invention, that others may, by applying current knowledge, readily adapt the same for use under various conditions of service.

10 I claim:

1. A swing comprising a supporting frame, a fixed gear carried at the top of said supporting frame, a seat supported in the frame below the axis of the fixed gear, bars pivotally connected with said seat and with said supporting frame coaxially with said fixed gear, a crank rotatably carried by said bars in offset relationship thereto and having a gear meshing with said first-mentioned gear, and bar means pivotally connected with said seat and with said crank at a point spaced from the first bars.

2. A swing comprising a supporting frame, a shaft mounted at the top of said supporting frame and provided with a fixed gear, a seat supported on the frame below the axis of the fixed gear, bars pivotally connected with said seat and with said shaft, a crank rotatably carried by said bars in offset relationship thereto and having a gear meshing with said first-mentioned gear, and bars pivotally connected with said seat and with said crank at a point spaced from the first bars.

3. A swing comprising a base having spaced upright supports, a shaft carried by the upper ends of said supports and having a fixed gear coaxially arranged therewith, bars pivotally connected with said shaft and depending therefrom, a seat, said seat being pivotally connected with the lower ends of said bars, brackets mounted on said bars, a crank rotatably journaled in said brackets and having a gear meshing with said fixed gear, and upright second bars pivotally connected at their upper ends with said crank shaft and at their lower ends with said seat laterally of said first-mentioned bars.
